UNITED STATES PATENT OFFICE.

DANIEL W. CAMPBELL, OF WEST TROY, ASSIGNOR OF ONE-HALF TO
FREDERICK H. STOWE, OF ALBANY, NEW YORK.

ORNAMENTAL FABRIC FOR TABLE-SPREADS.

SPECIFICATION forming part of Letters Patent No. 399,182, dated March 5, 1889.

Application filed April 28, 1888. Serial No. 272,125. (No specimens.)

To all whom it may concern:

Be it known that I, DANIEL W. CAMPBELL, of West Troy, in the county of Albany and State of New York, have invented a new and 5 useful Ornamental Fabric for Table-Spreads, of which the following is a full and exact description.

My invention relates to the ornamentation of table-spreads and other similar articles 10 made of felt, cloth, or other felted or woven goods, or in which said goods form the body-piece of the article; and it consists of a body-piece of any preferred size and form, having either plain or ornamental edges, and having 15 in its body a series of regularly-arranged incisions produced by cutters provided with either straight or ornamentally formed cutting-edges, and then weaving through said incisions ribbons or strips of material, preferably of some bright color that will form a good contrast with the color of the body-piece.

In the accompanying drawings, which are herein referred to and form part of this specification, Figure 1 is a plan view of one corner 25 of the body-piece of a table-spread having a series of incisions made therein. Fig. 2 is a like view of the same corner finished by weaving ribbons through said incisions. Fig. 3 is a section of Fig. 2 at the line X X. Fig. 4 is a 30 plan view of one end of the body-piece of a furniture-scarf, showing a series of preparatory incisions. Fig. 5 is a plan view of a strip of applique-work provided with a series of incisions through which the ornamenting- 35 ribbon is woven to secure said strip to the body-piece. Fig. 6 is a plan view of said furniture-scarf when finished by weaving the ornamenting-ribbon through the incisions of the body-piece and applique-strip; and Fig. 40 7 is a section of Fig. 6 at the line Y Y.

As represented in the drawings, A designates a body-piece for a table-spread or other article that it is desired to produce. Said body-piece is made of felt, cloth, or other similar fabric, and preferably of such fabric having a single color. Said body-piece may have its edges ornamenteally indented, as shown in the drawings, or left plain, at option. A series of incisions is made in said body-piece in such form 45 and at such places as the preferred style of ornamentation may require, and such incisions 50 may have the form of a straight line, (like those

indicated by 1,) of a curved line, (similar to those indicated by 2,) of a composite line, (similar to those indicated by 3 and 4,) or of 55 any other form that taste or fancy may suggest.

B and C are ornamenting ribbons or strips, preferably of a different fabric, and also, preferably, of a different color both in respect to each other and to the body-piece, so as to form a pleasing contrast of colors. Said ribbons are woven through the incisions of the body-piece, as shown in Figs. 2, 3, 6, and 7, so as to show alternately on the upper and 65 lower surfaces of said body-piece.

D is an applique-piece, which is preferably made of the same kind of fabric that the body-piece is, but of a different color. Said applique-piece has a series of incisions, 5, 70 which should correspond to those in that part of the body-piece where the applique-piece is to be secured, and the latter operation is effected by weaving the ribbon B through the incisions of the body and applique pieces, as 75 shown in Fig. 7, thereby simultaneously effecting the ornamentation of the article and securing the applique-piece to the body-piece.

The incisions are made in the fabric by means of cutters whose cutting-edges are fashioned to produce the desired form of incision, and said cutters may be arranged in series to produce all or any number of the incisions at one time, or be used singly to make one incision at a time, and said cutters may be either incorporated in a machine or be used by hand. I do not confine myself to the form of incision shown in the drawings, as a similar effect can be produced by diversifying the form of said incisions.

90 I claim as my invention—

The combination of a body-piece, of felt, cloth, or other felted or woven fabric, provided with a row of incisions, an applique-piece provided with incisions which correspond to the incisions in said body-piece, and a separable ribbon woven or drawn through said incisions, whereby said applique-piece is secured to said body-piece, as herein specified.

DANIEL W. CAMPBELL.
